PORTABLE FLASHLIGHT

Edward J. Garland, Worcester, and Wesley J. Officer, Hampden, Mass., assignors to Blake Manufacturing Corporation, Clinton, Mass., a corporation of Massachusetts

Application November 3, 1947, Serial No. 783,696

4 Claims. (Cl. 240—10.6)

1

This invention relates to portable flashlights. More particularly, the invention is directed to a novel snap-open and shut ring hanger and mounting therefor.

The main object of the invention is to provide a ring hanger for a flashlight which is mounted for rotary movement on the end wall of a flashlight cap, and in such manner that it can be swung to project vertically from the cap and to extend laterally beyond the casing, the hanger being normally retractably biased to lie flat against the cap wall.

It is a particular feature of novelty and advantage of the present invention to provide a ring hanger for a flashlight which is spring-biased in its snap-shut, retracted position and in its snap-open position. Because of the spring-biasing provided herein, the ring hanger will be snapped into its inoperative position and to its fully extended position and locked in such positions.

Yet another feature of novelty and advantage of the present invention is the provision of special spring-biasing means for a ring hanger in which the bail is journaled in a bushing extending outwardly from the cap wall, and is retained in snap-open and snap-shut position by a spring member associated therewith.

These and other desirable features of novelty and advantage of the present invention will be described in the accompanying specification, certain preferred forms being illustrated by way of example in the drawings, in which

Fig. 1 is an elevation of a flashlight with the end cap and ring hanger being shown in vertical section;

Fig. 2 is a detail in vertical section of the end cap showing the hanger in vertical position;

Fig. 3 is a view similar to Fig. 2 showing the hanger snapped into extended position;

Fig. 4 is a plan view of the end cap showing the ring hanger in closed position;

Fig. 5 is an elevation of a bottom portion of a flashlight with the end cap in vertical section, showing a modified form of ring hanger and snap-locking means;

Fig. 6 is a plan view of the end cap of Fig. 5, showing the ring hanger in closed position;

Fig. 7 is a vertical fragmentary section of the end cap of Fig. 6 showing the ring hanger in vertical position, and

Fig. 8 is a view similar to Fig. 7 showing the ring hanger biased in extended position.

Referring now to the drawings, in Figs. 1 to 4, there is shown a flashlight comprising a battery

2

casing 10, a top assembly 12, and an end cap 14 screw threaded onto the base of the casing 10. The cap 14 is provided with a wall portion 16 having a screw thread 18, a bead 20, and a depressed end wall 22. As shown in Fig. 2, a generally rectangular opening 24, formed in the end wall 22, along a diameter thereof, receives a raised loop 26 of a channel strip 28 having side walls or webs 30. The channel 28 has its free end 32 rolled over in bearing engagement with an inner portion 34 of the bead 20 of the end cap. A generally flat spring 36 is fitted in the channel member 28 and is secured thereto and to the end cap by rivet 38. At its other end the spring 36 is bowed away from the end wall, as indicated at 40, and is provided with a terminal section 42 providing a flat bearing surface for the ring hanger, as will now be described.

20 The ring hanger comprises a bail or annulus 44 (Fig. 4) conforming to the inner wall of section 20 of the end cap and bent inwardly at one side to form aligned sections 46 severally bent again at right angles to form parallel sections 48 which are inturned to form aligned journals 50, the latter being bent again at right angles to form parallel abutted end sections 52 forming a lever arm, the end faces 54 of which are adapted for sliding bearing engagement with bearing section 42 of the spring member and the adjacent terminal section 41 of the bowed portion 40 of the spring.

30 The action of the novel ring hanger described immediately above will be readily apparent from the above description and the drawings. The bail 44 is fitted in channelled spring holder 28 (Fig. 2) so that the aligned journals 50 of the bail have bearing engagement in the bushing section 26 of the spring support. The body 28 of the channel support is set into the cap and is abutted against the inside of end wall 22 with section 26 projecting through the aperture 24. Spring member 36 is fitted in channel member 28, both the spring 40 and the channel being provided with aligned apertures which are in alignment with a similar aperture in wall 22, the spring member being secured in interlocked position by rivet 38 passing through the said apertures and peened over or headed 45 against the end wall 22 and the spring 36. With the riveting of the channel support in place, the end 32 is locked in bearing engagement with the section 34 of the cap wall 20. The bail 44 is rotatable about an axis coincident with journals 50, and, when apposed to the end wall 22 of the

cap, the spring 36 will have its end portion 42 in spring bearing engagement with one side of the lever arm formed by apposed or terminal end sections 52 of the bail which will be locked in position therebetween. When the bail 44 is rotated to the vertical position shown in Fig. 2, the ends 54 of terminal ends 52 of the bail will have bearing engagement against the flat section 42 of the biasing spring 36. The biasing action of the spring 36 will maintain the bail 44 in position until it is rocked about its axis so that one side or the other of the end section 52 is engaged by bearing surface 40 of the spring, and the bail is snapped into nested position, as shown in Figs. 1 and 4. When the bail is extended in hanger position as shown in Fig. 3, the lever arm 52 will be resiliently clamped between section 41 of spring 36 and the angular rear wall 27 of the struck up bearing section 26 of channel 28. The positive bearing engagement of the spring and bail, and the journaling of the latter in bushing 28, assures positive snap lock performance and positive retention of the bail in either its shut position (Figs. 1 and 4), or its open position illustrated in Fig. 3. The combination of parts in the novel arrangement herein makes for simplicity in manufacture and assembly.

Referring now to Figs. 5 to 8, there is shown a modified form of ring hanger in which the end wall 22 of the cap is struck up to form a bearing or bushing section 22' which will receive the axes 46' of a bail or ring hanger 44'. The journals 46' have their terminal ends bent at right angles and apposed to form a lever arm 43' having an end bearing surface 54'. The latter is received in a channel end section 61 (Fig. 7) of a flat spring 60 which is secured to the cap wall 22 by the usual rivet 38. In this simple form of construction, the member 60 suberves the dual purpose of a spring-biasing member and a bail end-receiving and actuating member. The bail functions in this combination in essentially the same manner as that described above for Figs. 1 to 4, and provides the desirable internal spring bearing engagement with and against the bail while utilizing a fixed bushing or bearing associated with the end wall for receiving and supporting the journals of the bail.

It will be understood that the bail or ring hanger, while shown as generally circular, may assume other shapes without departing from the spirit of this invention.

It will be seen that there is provided devices in which the several objects of the invention are achieved and which are eminently fitted to meet the conditions of practical use.

As various modifications may be embodied in other specific devices, and as various changes may be made in the embodiments hereinabove set forth, it is to be understood that the devices illustrated and described herein are presented solely as illustrative of the invention and not in limitation thereof.

What is claimed is:

1. In a flashlight having a wall, a support member attached to the interior surface of said wall, said support member having a portion which extends exteriorly of said wall and provides a pair of journal bearings, the portion of said support member lying interiorly of said wall providing a

base for a spring member, a spring mounted on said support member, a bail, the two ends of which are bent into axial alignment to provide journals then bent angularly outwardly into parallel alignment to form a bearing member, the free end of said spring resiliently engaging said bearing member.

2. In a flashlight having an end wall, a support member attached to the interior surface of said wall, said support member having a portion which extends through and exteriorly of said wall and provides a pair of journal bearings, a spring mounted on the portion of said support member which is interior of said wall, a bail, the two ends of which are bent into axial alignment to provide journals, then bent angularly outwardly into parallel alignment to form a unitary bearing member, the said spring being fixed at one of its ends and having a free end mounted over and in resilient engagement upon said unitary bearing member.

3. In a flashlight having an end wall, a channelled support member attached to the interior surface of said wall, said support member having an angularly disposed ear which extends through and exteriorly of said wall and which is bent to provide a pair of journal bearings, a bail the two ends of which are bent into axial alignment to provide a pair of journals and are then bent angularly outwardly into parallel alignment to form a bearing member, a leaf spring supported in the channel of said support member, the said spring being attached to said support member at one end thereof and having its other end in resilient, sliding engagement with said bearing member.

4. In a flashlight end cap having an end wall, a relatively rigid, channelled support member, a leaf spring supported in the channel of said support member, fastening means for affixing said leaf spring to said support member adjacent a common end of each and means for affixing said support member to the interior surface of said wall, said support member having an angularly disposed ear which extends through a slot in said end wall and which is bent to provide a pair of journal bearings which are fixedly positioned exteriorly of said end wall, a bail having a portion adjacent each end thereof bent to provide a journal freely rotatable in one of said pair of journal bearings and having each end thereof then bent angularly outwardly, said outwardly bent ends being in parallel alignment with each other to form a bearing member which rotates around the axis of said journals but within said end cap, the free end of said leaf spring resiliently engaging said bearing member.

EDWARD J. GARLAND.
